UNITED STATES PATENT OFFICE.

JOHN J. COCHRAN, OF ST. LOUIS, MISSOURI.

MEANS FOR CREATING AND SUPPLYING EXPLOSIVE MIXTURE TO EXPLOSIVE- ENGINES.

1,102,475.

Specification of Letters Patent.

Patented July 7, 1914.

Application filed May 29, 1911. Serial No. 630,077.

To all whom it may concern:

Be it known that I, JOHN J. COCHRAN, a citizen of the United States of America, residing at St. Louis, in the State of Missouri, have invented certain new and useful improvements in Means for Creating and Supplying Explosive Mixture to Explosive-Engines, of which the following is a full, clear, and exact description, reference being had to the accompanying drawings, forming part of this specification.

My invention relates to means for mixing the fumes of hydrocarbon oils with air and then delivering the mixture of fumes and air to the cylinders of explosive engines, the improvement being more especially intended for use in supplying an initial quantity of explosive mixture to the cylinders of explosive engines for the purpose of providing for the engine being started without the necessity of resorting to the usual and common expedient of "cranking" the engine. The improvement is, however, of such nature as to provide for the supply of explosive mixture to the engine in sufficient quantity to meet all the needs of the engine when in full operation.

Figure I is in part an elevation and in part a vertical section illustrating my improvement, the engine shown illustrated diagrammatically. Fig. II is a vertical cross section through the distribution box. Fig. III is a vertical longitudinal section through the distribution box.

In the accompanying drawings:

A designates an engine which, in the example shown, comprises six cylinders designated 1, 2, 3, 4, 5, and 6.

7 designates the shell of a carbureter into which hydrocarbon oil is delivered from any suitable source of supply, preferably a tank, (not shown), communicating with a delivery pipe 8 that leads to a float box 9 in communication with the carbureter chamber, and in which is a float 10 that controls the level of oil maintained in the carbureter chamber. At the upper end of the carbureter chamber is a throat 11 that provides communication between said chamber and an explosive mixture conducting pipe 12 leading to a distribution box B into which explosive mixture is delivered by said pipe after it has been produced in the chamber of the carbureter. The distribution box B is placed in communication with

the several cylinders of the engine A by a series of delivery pipes 14 into which the entrance of explosive mixture is controlled in a manner to be hereinafter fully described.

15 designates a manifold communicable with the throat 11 at the upper end of the carbureter chamber and which may be cut off from communication with said throat by a throttle valve 16 operable in any suitable manner. The manifold 15 has connected to it a series of conducting pipes 17 that lead to the several cylinders of the engine A.

The explosive mixture produced in the operation of my apparatus is produced by the creation of an air circulation in the carbureter chamber that causes the volatile matter of the hydrocarbon oil therein to be drawn from the oil and delivered to the engine cylinders as fumes in contradistinction to the usual practice in carburization involving the atomization of the hydrocarbon oil and the delivery of the volatile matter of the oil mixed with air to the engine cylinders in the form of vapor. To derive the fumes from the hydrocarbon oil in the chamber of my carbureter, I make use of a nozzle 18 that extends through the carbureter and has an open discharge or jet end located in the throat 11 at the upper end of the carbureter chamber. During the operation of the engine, the cylinders are supplied with the explosive mixture through the medium of the pipes 17 which lead from the manifold 15, said mixture being drawn into the cylinders in a well understood manner while their pistons are on their suction stroke. Air is supplied to the carbureter nozzle through a pipe 19 provided with a spring actuated check valve which opens during the suction strokes of the engine.

An auxiliary pipe 7', leading to the interior of the shell 7, is provided with a check valve controlled by a spring which holds said valve on its seat during low speeds, but allows it to open during high speeds when the suction in the carbureter shell becomes excessive.

To start the engine, air under pressure is delivered to the nozzle 18 by suitable means such, for instance, as that shown, comprising an air conducting pipe 19 and a hand pump 20. It is obvious, however, that a mechanically operated pump may be utilized in lieu of the hand pump 20 and also that

a storage air reservoir may be utilized in connection with the air conducting pipe.

To facilitate the acquirement of fumes from a hydrocarbon oil in the chamber of my carbureter, I provide in conjunction with the carbureter shell a heating chamber 21, communicating with the exhaust pipe of the engine, said chamber being preferably located at the bottom of the shell, (see Fig. I). The carbureter shell is also provided with a chamber 21' through which a circulation of hot water or other fluid acquired in any suitable manner may be maintained to keep the hydrocarbon oil in a heated condition, so that fumes from the oil may be more readily and constantly obtained.

Each of the several explosive mixture conducting pipes 14 located between the cylinders of the engine and the distribution box B is supplied with controlling valves 22, all of which are operable by a shifter rod 23, through the medium of which the valves may be opened and closed to establish communication between the engine cylinders and distribution box, or discontinue such communication.

I will next proceed to the description of the distribution box B, which is present in my apparatus to provide for the proper delivery of explosive mixture to the cylinders of the engine when the engine is to be started. This distribution box comprises a shell 24, within which is a main inlet compartment 25, (see Figs. II and III), this compartment being in direct communication with the explosive mixture conducting pipe 12.

Located directly below the main compartment 25 is a series of passageways 26 which are always in communication with said main inlet compartment, the top wall of each passageway 26 being provided with a port 27. The passageways 26 lead from the delivery pipes 14 to a compartment 28 at the rear of the distribution box B and have valve seats 29 and 30 at their opposite ends, (see Fig. II). A ball valve 31 is loosely arranged in each passageway 26 so as to be free to roll from end to end thereof and abut one of the valve seats 29 and 30. When one of the balls 31 is located on a valve seat 30, an explosive mixture passing through the conducting pipe 12 and entering the main compartment 25 cannot pass into the pipe 14 adjacent to said valve seat 30, however when the ball is on the seat 29 an explosive mixture may be forced through the passageway 26 and pipe 14 communicating therewith.

The operation of this device as an engine starting apparatus is as follows: After the engine stops, all of the valves 22 are opened through the medium of the shifter rod 23 and explosive mixture will then pass from

certain cylinders into the pipes 14 leading therefrom. The pistons in the cylinders from which this explosive mixture flows are either on their compression stroke or their power stroke and the mixture is therefore under compression. It should be noted that the piston in one of the cylinders which gives up the explosive mixture is on its power stroke and that if this same mixture, or a fresh mixture, is introduced into said cylinder it may be ignited with the result of starting the engine. Assuming that three of the cylinders contain a compressed charge which passes into three of the pipes 14 upon the opening of valves 22; three of the ball valves will then be forced to the seats 29 at the rear of passageways 26 and the mixture will pass through port 27, enter the main compartment 25, and return to the carbureter shell through the pipe 12. While these three balls are being forced rearwardly toward the seats 29 a certain amount of the compressed mixture will pass the balls and escape into the rear compartment 28; the other three balls will therefore be forced against the valve seats 30 by pressure from the rear compartment. It should now be understood that three of the ball valves 31 are positioned to allow an explosive mixture to pass from the main compartment 25 to the cylinders which contained the compressed mixture, while the other three balls are located on the seats 30 so as to prevent the mixture from passing into the other cylinders. To start the engine, the pump 20 is operated to force air through the carbureter nozzle 18 and delivery pipe 12, this air carrying with it fumes of the hydrocarbon oil in the carbureter chamber, thereby producing an explosive mixture which is delivered to the distribution box B under pressure. This mixture enters the main compartment 25, passes into certain passageways 26, and is finally delivered to certain cylinders through pipes 14. The ball valves 31 are positioned to allow the mixture to flow to the three cylinders from which the compressed charge escaped, the pipes 14 leading to the other cylinders being closed by ball valves. After the explosive mixture has been forced into the cylinders by the pump 20, the throttle valve 16 is opened, all of the valves 22 are closed and to start the engine it is then only necessary to ignite the charge in one of the cylinders in the ordinary manner. The first three power strokes are caused by exploding the mixture which has been forced through the distribution box, but thereafter the mixture is drawn into the cylinders through pipes 17 during the suction strokes in the usual manner.

I claim:—

1. An apparatus for starting explosive engines comprising a distribution box having a main compartment, a series of pas-

sageways communicating with said main compartment, and a second compartment communicating with one of the ends of each of said passageways; pipes leading from the other ends of the passageways and adapted to communicate with the engine cylinders, valves arranged in said passageways and adapted to close either end thereof, and means for forcing an explosive mixture to said main compartment.

2. An apparatus for starting explosive engines comprising a distribution box having a main compartment, a series of passageways communicating with said main com-

partment and a second compartment communicating with one of the ends of each of said passageways; pipes leading from the other ends of the passageways and furnishing communication with the engine cylinders, ball valves arranged in said passageways and adapted to close either end thereof, and means for forcing an explosive mixture to said main compartment.

JNO. J. COCHRAN.
